[57] CLAIM

The ornamental design for a bottle, as shown and described.

DESCRIPTION

FIG. 1 is a front elevation view of a bottle embodying my new design;

FIG. 2 is a top view thereof;

FIG. 3 is a rear elevation view thereof;

FIG. 4 is a bottom view thereof;

FIG. 5 is a side elevation view thereof;

FIG. 6 is a side elevation view of the side opposite that shown in FIG. 5;

FIG. 7 is a front perspective view thereof;

FIG. 8 is a front elevation view of a bottle embodying a second embodiment of my design;

FIG. 9 is a top view of the embodiment of FIG. 8;

FIG. 10 is a rear elevation view of the embodiment of FIG. 8;

FIG. 11 is a bottom view of the embodiment of FIG. 8;

FIG. 12 is a side elevation view of the embodiment of FIG. 8;

FIG. 13 is a side elevation view of the side opposite that shown in FIG. 12;

FIG. 14 is a front perspective view of the embodiment of FIG. 8;

FIG. 15 is a front elevation view of a bottle embodying a third embodiment of my design;

FIG. 16 is a top view of the embodiment of FIG. 15;

FIG. 17 is a rear elevation view of the embodiment of FIG. 15;

FIG. 18 is a bottom view of the embodiment of FIG. 15;

FIG. 19 is a side elevation view of the embodiment of FIG. 15;

FIG. 20 is a side elevation view of the side opposite that shown in FIG. 19;

FIG. 21 is a front perspective view of the embodiment of FIG. 15;

FIG. 22 is a front elevation view of a bottle embodying a fourth embodiment of my design;

FIG. 23 is a top view of the embodiment of FIG. 22;

FIG. 24 is a rear elevation view of the embodiment of FIG. 22;

FIG. 25 is a bottom view of the embodiment of FIG. 22;

FIG. 26 is a side elevation view of the embodiment of FIG. 22;

FIG. 27 is a side elevation view of the side opposite that shown in FIG. 26;

FIG. 28 is a front perspective view of the embodiment of FIG. 22;

FIG. 29 is a front elevation view of a bottle embodying a fifth embodiment of my design;

FIG. 30 is a top view of the embodiment of FIG. 29;

FIG. 31 is a rear elevation view of the embodiment of FIG. 29;

FIG. 32 is a bottom view of the embodiment of FIG. 29;

FIG. 33 is a side elevation view of the embodiment of FIG. 29;

FIG. 34 is a side elevation view of the side opposite that shown in FIG. 33; and

FIG. 35 is a front elevation view of the embodiment of FIG. 29.
